UNITED STATES PATENT OFFICE.

JOHNIE B. HALEY, OF JAVA, VIRGINIA.

WRENCH.

1,136,599.

Specification of Letters Patent. Patented Apr. 20, 1915.

Application filed May 8, 1914. Serial No. 837,276.

To all whom it may concern:

Be it known that I, JOHNIE B. HALEY, a citizen of the United States, residing at Java, in the county of Pittsylvania and State of Virginia, have invented certain new and useful Improvements in Wrenches, of which the following is a specification, reference being had to the accompanying drawings.

This invention relates to new and useful improvements in wrenches, the main object of the present invention being the provision of a wrench which is particularly adapted for use in manipulating nuts, pipes, rods or the like and, at the same time provide a wrench which can be quickly and readily operated to accommodate for various size objects upon which the wrench is to be used.

Another object of the invention is the provision of a tool of the above character which will possess advantages in points of efficiency and durability, is inexpensive to manufacture and at the same time is simple in construction and operation.

With the above and other objects in view, the invention consists in the novel features of construction and the combination and arrangement of parts to be hereinafter more fully described, pointed out in the claims and shown in the accompanying drawings, in which

Figure 1 is a side elevation of a wrench constructed in accordance with my invention parts thereof being broken away and illustrated in cross section; Fig. 2 is a rear elevation; Fig. 3 is a front elevation.

Referring more particularly to the drawings, 1 indicates the shank at one end of which is formed a handle 2 and at the other end is formed a stationary jaw 3. Arranged in parallel relation with the shank 1 is the movable shank 4 and carried thereby is a sleeve 5 which is adapted to inclose the shank 1 whereby two shanks are securely held in their respective positions. The shank 4 is provided at its outer end with the jaw 6 which is movable with respect to the jaw 3 and is securely held in various positions by means of the teeth 7 formed on the movable shank 4 which are adapted for engagement with the teeth 8 on the shank 1. The movable shank 4 is mounted upon a pin 9 carried by the sleeve 5, for pivotal movement and in order to normally retain the teeth 7 and 8 into engagement, I provide a spring member 10, one end of which is rigidly secured to the inner side of the movable shank

4 while the other end thereof yieldingly bears against one face of the shank 1 so as to yieldably retain the teeth of the shank 4 into engagement with the teeth on the shank 1.

In the ordinary use of the wrench, the resiliency of the spring 10 is sufficient to retain the teeth 7 and 8 into engagement and hold the jaw 6 in its respective adjusted position but should the wrench be used on heavy work, I provide a locking member 11 which is in the form of a bell crank pivotally mounted upon the inner end of the shank 4 and the inner end thereof is adapted for engagement with the inner face of the shank 1 to securely retain the teeth 7 into engagement with the teeth 8 to hold the shank 4 against longitudinal movement with respect to the shank 1. The inner end of the shank 4 is provided with a curved handle portion 12 which is adapted to be engaged by any one of the fingers of the hand to release the teeth 7 and 8 whereby the shank 4 may be adjusted longitudinally with respect to the shank 1.

It will be noted that in operating the locking member 11, the outer end thereof, when the device is in its normal position, extends outwardly beyond the outer face of the shank 4 and when it is desired to place the same in its operative position, pressure is exerted upon the outer end of the locking member so that the inner end thereof will engage the inner face of the shank 1 and force the inner end of the shank 4 outwardly, thus securely engaging the teeth 7 with the teeth 8 to hold the shank 4 against any longitudinal movement.

In connection with the above described wrench, I provide first a sleeve 13 which is preferably U-shaped and the ends thereof are rigidly secured to the outer side of the shank 1 adjacent the rigid jaw 3. Pivoted between the two side portions of the sleeve 13 are the substantially circular head members 14 and 15, the upper and lower faces respectively of said head members being provided with teeth 14' and 15' which are adapted to mesh so that upon actuating the handle 16 which is formed integral with the head 14, the two head members will be rotated in opposite directions. Formed integral with the head 15 is a shank 17 having a curved jaw 18 formed integral therewith which is provided upon its inner face with a plurality of teeth 19 which are

adapted to co-act with the teeth 20 formed in the concave jaw portion 21 upon the rear face of the jaw 3.

The outer portions of the jaws 18 and 21 are provided with cutting edges 22 which are formed similar to cutting pliers now in use so that the same may be readily used for pulling nails, cutting wire or for any other similar purpose. The shank 17 and the jaw 3 are provided with co-acting cutting surfaces 23 wherein wire may be readily cut when desired. The head 14 is provided upon its inner face with a concave jaw portion 24 having teeth 25 which are adapted to co-act with the teeth 26 in the jaw 27 which is formed upon the outer face of the shank 1 just below the inner end of the sleeve 13. The co-acting jaws 18 and 21 and 24 and 27 are adapted for manipulating pipe, rods and various other similar articles which can not be readily gripped by the jaws 3 and 6. In actuating the jaws 18 and 21 and 24 and 27, the handle member 16 is moved laterally with respect to the handle member 2 so that the jaws may be readily engaged or disengaged with the jaws to be manipulated.

From the above description taken in connection with the accompanying drawing, it will be readily apparent that I have provided a simple and durable wrench wherein different types of objects of various sizes may be readily manipulated when desired. It will be apparent that my device is so constructed that it may be quickly and readily operated and at the same time is simple in construction and can be manufactured at a comparatively low cost.

While I have shown and described the pre-

ferred form of my invention, it will be obvious that various changes in the details of construction and in the proportions may be resorted to for successfully carrying my invention into practice without sacrificing any of the novel features or departing from the scope of the appended claims.

45

What I claim is:—

A device of the class described including a shank having teeth upon one face and a rigid jaw at one end, a movable shank, a sleeve carried thereby and adapted to 50 enclose the stationary shank, a jaw carried by the movable shank, said movable shank being mounted for pivotal movement within the sleeve and having teeth adapted to engage the teeth on the first shank, a spring 55 member having one end rigidly secured to the inner face of the movable shank and having its free end yieldably engaging the stationary shank, a handle portion formed integral with the movable shank, a locking 60 lever pivotally mounted upon said handle, said locking lever including a bell crank having its outer end normally projecting beyond the outer face of the handle and its inner end adapted for engagement with one 65 face of the stationary shank to securely retain the teeth on the aforesaid shanks into engagement to prevent longitudinal movement of the movable shank with respect to the stationary shank.

In testimony whereof I hereunto affix my signature in the presence of two witnesses.

JOHNIE B. HALEY.
